(57) **CLAIM**

The ornamental design for a medical device control unit display screen with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a medical device control unit display screen with graphical user interface, showing a first embodiment of the new design; and,

FIG. 2 is a front view of a second embodiment thereof.
